HOOD FOR A HAIR DRYER

Raymond Descaries, Montreal, Quebec, Canada, assignor to Aktiebolaget Electrolux, Stockholm, Sweden, a corporation of Sweden

Filed Aug. 15, 1961, Ser. No. 66,364

Term of patent 14 years

(Cl. D86—10)

FIG. 1 is a side elevational view of a hood for a hair dryer showing my new design;

FIG. 2 is a rear elevational view thereof;

FIGS. 3 and 4 are respectively top and bottom plan views thereof perpendicular to its longitudinal axis; and

FIGS. 5 and 6 are sectional views respectively taken at lines 5—5 and 6—6 of FIG. 3.

I claim:

The ornamental design for a hood for a hair dryer, as shown.
